UNITED STATES PATENT OFFICE.

JOHN C. UHLEIN, OF WATERTOWN, NEW YORK.

NON-REFILLABLE BOTTLE.

1,210,728.

Specification of Letters Patent. Patented Jan. 2, 1917.

Application filed January 21, 1916. Serial No. 73,382.

To all whom it may concern:

Be it known that I, JOHN C. UHLEIN, a citizen of the United States, residing at Watertown, in the county of Jefferson and State of New York, have invented certain new and useful Improvements in Non-Refillable Bottles, of which the following is a specification, reference being had therein to the accompanying drawing.

This invention relates to new and useful improvements in non-refillable bottles and consists of a simple and efficient device of this nature having various details of construction, combinations and arrangements of parts which will be hereinafter fully described, shown in the accompanying drawings and then specifically defined in the appended claims.

I illustrate my invention in the accompanying drawings, in which:

Figure 1 is a central vertical sectional view through a neck of a portion of the bottle. Fig. 2 is a sectional view through the upper portion of the valve retaining part of the neck. Fig. 3 is a sectional view through a disk and valve seat. Fig. 4 is a plan view of the disk, and Fig. 5 is a plan view of the part shown in section in Fig. 2.

Reference now being had to the details of the drawings by letter, A designates a bottle having a stub neck B circumferentially threaded and adapted to be engaged by the threads formed in the inner surface of the neck C. Said neck has a shoulder D formed therein and the neck is designed to contain the operative parts of the device. A valve retaining member E, having a tapering apex, is inserted within the neck of the bottle and is adapted to bear against said shoulder, as shown clearly in Fig. 1 of the drawings, and said member is provided with legs F, shown clearly in Figs. 2 and 5, which are spaced apart, leaving sufficient means for allowing the liquid to pass out between said legs, which latter project beyond the circumference of the member, as shown in Fig. 5. A circular-outlined shell K is provided with legs N projecting at right angles therefrom and spaced apart, the upper ends of said legs being inclined and slightly concaved as at N' and provided with notches I and a central opening O. The marginal edge of said opening forms a seat for the hollow valve R, the lower end of which is formed on the arc of a sphere, the point of contact be-

tween said spherical portion and the valve seat being a true circle when properly ground, thus making a tight joint. It will be noted that a chamber is provided intermediate the legs N and the bell retaining member E in which a gravity ball T is mounted and which tends to normally hold the hollow valve R seated when the bottle is in an upright or in a position inclined down below horizontal plane. A washer P, preferably of cork or other suitable material, is placed upon the inner end of the stub neck B and, when the neck is screwed over the part B, a hermetically sealed joint will be afforded. It will be noted upon reference to Fig. 2 of the drawings that at the free ends of the legs F are ribs H which are designed to engage said recesses or notches I formed in the upper ends of the legs N.

When the parts are assembled, the neck C is designed to be securely held in place by cement, making it impossible to remove the same without being broken. The valve will be normally held seated by the gravity ball. In the event of it being desired to dispense liquid from the bottle, it may be done by tilting the bottle until it assumes such a position that the ball will be free from the valve, allowing the latter to unseat. The spaces between the legs N and between the legs F will allow the liquid to be dispensed without interference. In the event of it being desired to refill the bottle, when held in a position inclined toward the horizontal, the inclined surface of the member E will cause the ball to roll against the valve and hold the same seated. In the event of an attempt being made to refill the bottle when inverted and by creating a vacuum, the valve being hollow and independent of the weight will float and, as the liquid rises in the neck, the valve will be lifted to its seat, thus effectually closing the opening.

What I claim to be new is:—

1. A non-refillable bottle having a neck with a shell therein, provided with a central aperture, the marginal edge of which forms a valve seat, said shell having arms projecting therefrom which are spaced apart and their opposite faces tapering, the upper end of each arm concaved, a hollow valve with a semi-spherical end adapted to seat on the marginal edge of the opening in the shell, a gravity valve-closing ball and a conical-

shaped ball retaining member fitted within the neck and provided with arms which are concaved upon their inner faces and designed to coöperate with the curved portions of said arms upon the shell to cause the valve to be seated when the bottle is in an upright or horizontal position, a portion of the inner surface of the neck having a shoulder against which the legs of the ball retaining member are adapted to contact to retain the same within the neck.

2. In combination with a bottle having a stub neck, circumferentially threaded, a neck 5 interiorly threaded and engaging said stub neck and shouldered upon its inner surface, an apertured washer resting upon the upper end of said stub neck, a shell resting upon said washer and provided with a central opening, said shell having legs projecting 10 from its upper surface and spaced apart, said legs provided with inclined sides and their upper portions concaved, the upper end of each leg being notched, a conical-shaped ball retaining member provided with downwardly extending arms spaced apart and each terminating in a contracted portion 15 adapted to rest in said notches, a hollow valve with a semi-spherical end designed to seat upon the marginal edge of the opening in said shell, and a weighted member confined between the valve and said conical-shaped member and normally holding the valve seated.

3. In combination with a bottle having a

stub neck, circumferentially threaded, a neck 35 interiorly threaded and engaging said stub neck and shouldered upon its inner surface, an apertured washer resting upon the upper end of said stub neck, a shell resting upon said washer and provided with a central 40 opening, said shell having legs projecting from its upper surface and spaced apart, said legs provided with inclined sides and their upper portions concaved, the upper end of each leg being notched, a conical-shaped ball retaining member provided with downwardly extending arms spaced apart and each terminating in a contracted portion 45 adapted to bear against the shoulder inside the neck, the inner face of each arm concaved, a hollow valve with its lower end semispherical-shaped and normally resting upon the marginal edge of the opening in the shell, and a ball guided by the concaved portions 50 of said arms upon the shell toward the top of the outer end of the valve, said ball having a limited movement intermediate the valve and the conical-shaped end of said member.

In testimony whereof I hereunto affix my signature in presence of two witnesses.

JOHN C. UHLEIN.
